[57] CLAIM

We claim the ornamental design for a multimedia unit, as shown and described.

DESCRIPTION

FIG. 1 is a front, right perspective view of a multimedia unit showing our new design;

FIG. 2 is a top view thereof;

FIG. 3 is a front view thereof;

FIG. 4 is a left side view, the opposite side view being a mirror image thereof;

FIG. 5 is a bottom view thereof;

FIG. 6 is a perspective view thereof showing the visual display in a tilted position;

FIG. 7 is another perspective view thereof;

FIG. 8 is a front right perspective view of another embodiment thereof the front left perspective view being a mirror image;

FIG. 9 is a top view thereof; and,

FIG. 10 is a front view thereof.

The rear of the unit in both embodiments is substantially plain and unornamented.

The dotted line showing is for environmental purposes only and does not form a part of the design.
